CLAIM

The ornamental design for a hydraulic power unit for a differential, as shown and described.

DESCRIPTION

FIG. 1 is a first perspective view of a hydraulic power unit for a differential showing our new design.

FIG. 2 is a second perspective view of the hydraulic power unit for a differential of FIG. 1.

FIG. 3 is a top view of the hydraulic power unit for a differential of FIG. 1.

FIG. 4 is a front view of the hydraulic power unit for a differential of FIG. 1.

FIG. 5 is a rear view of the hydraulic power unit for a differential of FIG. 1.

FIG. 6 is a first side view of the hydraulic power unit for a differential of FIG. 1; and,

FIG. 7 is a second side view of the hydraulic power unit for a differential of FIG. 1.

Any portion of the hydraulic power unit for a differential shown in broken lines is for the purpose of illustrating environmental structure and forms no part of the claimed design.
